UNITED STATES PATENT OFFICE.

ROBERT C. MURRAN, OF BROOKLYN, NEW YORK.

HEDGE-TRIMMER.

1,115,328.

Specification of Letters Patent. Patented Oct. 27, 1914.

Application filed February 17, 1914. Serial No. 819,248.

To all whom it may concern:

Be it known that I, ROBERT C. MURRAN, a citizen of the United States, residing at Brooklyn, in the county of Kings and State of New York, have invented new and useful improvements in Hedge-Trimmers, of which the following is a specification:

The general object of this invention is to refine the construction of hedge trimming machines in point of simplicity of parts and in cheapness of manufacture.

A further object of the invention is the provision of such a machine which may be adjusted in a simple manner, whereby the same may be used for trimming bushes in various desired styles and shapes. And to these ends the invention consists of a flexible base plate on which is mounted a flexible reciprocating saw-member and an adjustable means for causing the base plate and saw-member to assume a bowed-shape.

Other objects will appear and be better understood from that embodiment of my invention of which the following is a specification, reference being had to the accompanying drawings forming part hereof, in which:

Figure 1 is a top plan view of the device with a portion broken away for the sake of clearness; Fig. 2 is a side elevational view of Fig. 1; Fig. 3 is an enlarged detail proportional plan view of the device; and Fig. 4 is a cross sectional view taken on the line 4-4 in Fig. 3.

As shown in the drawings the device is composed of the base plate 5, a cutter 6, a guard 7, and the flexing member 8. The base plate 5 may be formed of any suitable flexible material but it is preferred to use saw steel by virtue of the resiliency of this metal. One edge of the base is provided with a series of serrations or teeth 9, and to one end of the base is secured a suitable handle 10 for the purpose of carrying the device in the hand.

As shown in the drawings the guard plate 7 is not as wide as the base and for the purpose of illustration it is shown approximately half as wide. The guard is formed of material similar to the base plate and is provided with teeth 11 corresponding in shape to the teeth 9 of the base. The guard and base are positioned in spaced relation to each other, as shown in Fig. 4 and to admit of this a fillet 12 is secured to the end of each tooth, thus forming a pocket 13 between

the guard and the base, for the reception of the cutter 6. In order to reinforce the back edge of the guard plate a rib 14 is mounted thereon the entire length of the guard and coincident with the edge thereof and is secured to the guard plate at suitable locations such as by the rivets 15.

The cutter 6 is formed preferably of resilient tempered metal, such as saw-steel, and is provided at one edge with the saw-teeth 16 which are provided with suitable cutting edges 17. These teeth are adapted to be located within the pockets 13 and be reciprocated therein. It will be noted that the teeth 16 and 11 of the base and guard respectively, co-operate to form jaws a, which being longer than the cutting-teeth 16 provide spaces for the retention of shrub-branches when the cutter is being operated to shear off the branches thereof as in the case of trimming a hedge or the like.

The cutter is retained on the base 5 by the screw 18 carried by the base and which projecting through the cutter is surmounted by a thumb nut 19, and in order not to bind the cutter against the base a spring 20 is provided on the screw for the purpose of bearing against the gasket 21 and thus by regulating the screw-nut 19 the friction between the cutter and the base may be adjusted.

A longitudinally disposed slot 22 is provided in the cutter for the reception of the screw 18 and by virtue of this slot the cutter may be slidably retained in place on the base. It will be seen also that by unscrewing the nut 19 from its position the cutter may be detached from the base 5 and removed for sharpening or like purposes.

Located at the end of the device and also adjacent to the handle 10 is a pair of upright brackets 23-23, in each of which is pivotally carried a rod 24 which are disposed opposingly as shown. These rods are screw-threaded oppositely and are joined by a sleeve or turn-buckle 25, which when rotated, varies the spaced relation of the two uprights 23. It will be noted especially by referring to Fig. 2, that upon rotating the sleeve-nut 25 so that the brackets tend to separate from each other, the base, the guard and the cutter assume a bowed shape, and obviously upon shortening the rods 24 the flexure becomes normal or straight.

Mounted on the base adjacent to the handle is a pivoted wheel or disk 26 which eccentrically carries a pitman 27 pivotally se-

cured to the cutter for the purpose of operating the same. The wheel is rotated through a flexible shaft 28 by any suitable means such as by hand-power, electric-motor, or the like, 5 and is adapted to reciprocate the cutter as previously described.

What is claimed as new is:

1. A bush trimmer comprising a flexible base provided with a handle, and also provided with laterally extending teeth at one edge thereof, a flexible guard secured on one side of the base and in spaced relation therewith and provided with laterally extending teeth conforming in shape and position to the teeth of the base, a flexible cutter slidably secured to the base and provided with cutting teeth adapted to reciprocatingly operate between the guard and the base, means carried by the base for reciprocating the cutter, and means carried by the base for flexing the base, the guard and the cutter substantially as described.
2. A bush trimmer comprising a flexible base provided with a handle and also provided at one edge with laterally disposed teeth, a flexible guard plate secured to the

surface of the base in spaced relation therewith and provided with laterally disposed teeth conforming in shape and position with the teeth of the base, a fillet securing the ends of the teeth of the base and the guard and providing pockets between the guard and base, a flexible cutter slidably and detachably secured to the base and provided with cutting teeth fitted in the said pockets and adapted to reciprocate therein; means carried by the base for reciprocating the said cutter, and means for flexing the base, the guard and the cutter, said means consisting of an upright located at each end of the base, screw-threaded rods pivotally carried by the uprights, and a sleeve connecting the rods and adapted to adjust the rods in relation to each other substantially as described.

In testimony whereof I affix my signature in presence of two witnesses.

ROBERT C. MURRAN.
